ROTARY BRUSH CONSTRUCTION

Ruben O. Peterson, University Heights, Ohio, assignor to
The Osborn Manufacturing Company, Cleveland, Ohio,
a corporation of Ohio

Application July 12, 1950, Serial No. 173,464

11 Claims. (Cl. 15—182)

This invention relates as indicated to rotary brush construction and, more particularly, to a pre-assembled rotary brush unit adapted to be mounted upon an arbor or mandrel and readily removed therefrom when it is desired to replace the same.

Power driven rotary brushes mounted upon shafting are commonly employed for a wide variety of purposes including the surface conditioning of metal sheets and the like and some such brushes, commonly cylindrical in form and known as "roller" brushes, are quite large and heavy. They may be comprised of a number of annular brush sections assembled in close side-by-side relationship or a relatively long length of helically wound brush strip may be utilized. In the latter case, the same may be wound upon a tubular core adapted closely to fit a relatively large diameter arbor or to be supported upon a relatively small diameter arbor by means of annular adapters. The assembly and disassembly of such brushes has always constituted something of a problem when it is desired to replace a worn-out brush with a new brush or to substitute a different size brush on the arbor. In my co-pending application Serial No. 732,445, filed March 5, 1947, now Patent No. 2,609,559, I disclose a novel form of rotary brush including retaining means considerably simplifying the mounting and replacement of this type of brush while at the same time providing a very strong assembly adapted to withstand high speed operation and the stresses and strains to which the same is subjected in use.

It is a principal object of this present invention to provide a replaceable pre-assembled brush unit which may be quickly installed and removed without difficulty and without the necessity of employing special tools.

Another object is to provide means whereby helically wound brush strip is permanently secured to a tubular core for mounting as a unit on either a large or small diameter arbor.

Still another object is to provide such brush unit adapted to be mounted upon and driven by a variety of different types of arbors including square, polygonal and round arbors.

A further object is to provide such brush unit which is designed for passage of a fluid, either gaseous or liquid therethrough for cooling and other purposes.

Other objects of my invention will appear as the description proceeds.

To the accomplishment of the foregoing and related ends, said invention then comprises the features herein-after fully described and particularly pointed out in the claims, the following description and the annexed drawings setting forth in detail certain illustrative embodiments of the invention, these being indicative, however, of but a few of the various ways in which the principle of the invention may be employed.

In said annexed drawing:

Fig. 1 is an end elevational view of another rotary brush unit embodying the principles of my invention;

2

Fig. 2 is a sectional view taken along the line 2—2 on Fig. 1;

Fig. 3 is a fragmentary sectional view taken along the line 3—3 on Fig. 1;

Fig. 4 is a fragmentary perspective view of the tubular core of the brush of Fig. 1;

Fig. 5 is a transverse sectional view through a circular arbor and such core mounted thereon;

Fig. 6 is a view resembling Fig. 5 but showing such core mounted on a different type of arbor; and

Fig. 7 is a view similar to Fig. 5 but showing such core mounted on a substantially square arbor.

Referring now more particularly to said annexed drawing and especially Figs. 1—3 thereof, the brush construction there illustrated comprises a cylindrical sheet metal core 23 having a length of helically wound brush strip 2 seated thereon. Such brush strip may desirably be of the general type illustrated and described in my Patent No. 2,303,386 having a sheet metal channel form base 3 and stranded brush material 4 doubled and retained therein beneath an elongated retaining element such as wire 5. Such wire in turn may be secured in place by means of overlapping teeth 6 punched in from the respective sides of channel 3. Other types of brush strip having brush backs similar to channel 3 are well known in the art and may likewise be employed in the construction of this invention.

I prefer to form such core of two identical stampings, each making up one-half of the cylindrical core. Each such stamping is of general semi-circular cross-section formed with an inwardly protruding rib 24 extending longitudinally thereof midway of its width. A complementary groove 25 is thus formed externally of such rib. The longitudinal edge portions of such stamping are offset inwardly and such edge portions of two opposed stampings joined as by spot welding to form inwardly protruding ribs 26 similar in size and conformation to ribs 24, with complementary grooves 27 externally thereof similar to grooves 25.

Slots 28 are formed in the ends of the tubular core member thus obtained intermediate such ribs 24 and 26 for a purpose to be explained below. A helically wound length of brush strip generally indicated at 2 is now tightly seated on the outer periphery of such core 23 and the outermost turn (or, if desired, several turns) is welded to such core, preferably by arc welding, through such slots 28.

A brush unit of the type described may then be seated on an appropriate arbor as illustrated in Figs. 5, 6, and 7, for example (the core portion of such brush assembly only being shown in such figures). Thus, in Fig. 5 the ribs 24 and 26 are seated on arbor 29 of circular cross-section with key 30 inserted in a keyway in such arbor being adapted to contact any one of such ribs in driving engagement. In Fig. 6, core 23 is shown mounted upon a generally square arbor 31 having the corners of the latter rounded to conform to the inner periphery of such core with ribs 24 and 26 contacting the flats on such arbor therebetween. Fig. 7 shows core 23 mounted on a square arbor 32 having its corners only relatively slightly broken or rounded to engage the inner periphery of such core with corner edges of ribs 24 and 26 engaging the flats of the arbor in order that the brush may be driven thereby.

For many purposes a brush unit of the type illustrated in Figs. 1—7 inclusive may be mounted upon an arbor and secured in position thereon by employment of the usual large nuts commonly employed threaded on the arbor. In some instances, however, it will be desirable also to employ toothed end plates of the type disclosed in my co-pending Patent No. 2,609,559 above referred to. In the past, when it has been desired to mount a long "roller" type brush as a unit upon a closely fitting arbor,

considerable difficulty has been met with due to the tendency of the brush core to bind thereon. The provision of longitudinally extending ribs 24 and 26 entirely eliminates this problem, such ribs serving as runners and greatly reducing the area of the contacting surfaces. A plurality of spaced holes may be provided in core 23 to permit the radial outward flow of air or other fluid media to the brush element mounted thereon.

It will be seen from the foregoing that I have provided an improved brush construction whereby a helically wound length of brush strip may be mounted on a generally cylindrical core and made integral therewith so that the brush may be handled as a unit even when of very large size. The advantages of this arrangement, particularly over that usually employed where the helically wound brush strip is mounted directly on the arbor, have been explained above. From a practical operating point of view, the fact that brushes of this type may be removed and replaced upon their arbors with a minimum of down time has been found to be of very great value.

It will, of course, be understood that the term "brush" as used herein and in the claims is intended to include closely related articles such as rotary buffs, the particular filler material not constituting any part of the present invention. Helically wound brush strip manufactured in accordance with my prior Patent 2,303,386, for example, is relatively inexpensive of manufacture, as are also the stampings such as core members 23. When rigidly assembled, as by welding, a complete brush unit is produced at low cost which nevertheless will withstand difficult operating conditions. Generally flat annular end members may be mounted on the arbor to either side of the brush unit of Figs. 1 and 2 or secured thereto by welding. Intermediate turns of the helical brush strip may be welded to the generally cylindrical core through holes in core 23. This is often desirable in the case of relatively long "roller" brushes. Reference may be had to my co-pending divisional application Serial No. 561,446, filed January 26, 1956, for another form of brush assembly which is particularly advantageous where it is desired to mount an annular rotary brush unit of large inner diameter on an arbor which may be of relatively small diameter.

Other modes of applying the principle of the invention may be employed, change being made as regards the details described, provided the features stated in any of the following claims or the equivalent of such be employed.

I therefore particularly point out and distinctly claim as my invention:

1. A rotary brush unit comprising a cylindrical core and a helically wound length of brush strip having a metal back seated on the outer periphery of said core with brush material extending generally radially therefrom, said core comprising two opposed identical sheet metal stampings of general half-circular cross-section with inwardly offset longitudinal edge portions overlapping and welded together, thereby providing two diametrically opposite inwardly protruding ribs, inwardly protruding longitudinally extending ribs of like dimensions formed in each of said stampings midway between said first-named ribs, said ribs being adapted to engage and seat upon an arbor inserted axially within said core, slots in the ends of said core, weld metal in said slots securing such metal back firmly to said core, and openings through the wall of said core adapted to permit radially outward flow of fluid entering said core axially into the spaces between said core and such arbor.

2. A rotary brush unit comprising a cylindrical core and a helically wound length of brush strip having a metal back seated on the outer periphery of said core with brush material extending generally radially therefrom, said core comprising two opposed identical sheet metal stampings of general half-circular cross-section with inwardly offset longitudinal edge portions overlapping and welded together, thereby providing two diametrically opposite

inwardly protruding ribs, inwardly protruding longitudinally extending ribs of like dimensions formed in each of said stampings midway between said first-named ribs, said ribs being adapted to engage and seat upon an arbor inserted within said core, the end turns of such helically wound brush strip metal back being welded to said core.

3. A rotary brush unit comprising a cylindrical core and an annular brush element seated on the outer periphery of said core with brush material extending generally radially therefrom, said core comprising two opposed identical sheet metal stampings of general half-circular cross-section with inwardly offset longitudinal edge portions overlapping and welded together, thereby providing two diametrically opposite inwardly protruding ribs, inwardly protruding longitudinally extending ribs of like dimensions formed in each of said stampings midway between said first-named ribs, said ribs being adapted to engage and seat upon an arbor inserted within said core.

20 4. A rotary brush unit comprising a cylindrical core and an annular brush element seated on the outer periphery of said core with brush material extending generally radially therefrom, said core comprising a sheet metal cylinder having a plurality of inwardly projecting exposed ribs of substantial width formed therein by deformation of the sheet metal of said cylinder and extending generally parallel to the axis thereof adapted directly to engage and seat upon a power driven shaft inserted co-axially within said core.

25 5. A rotary brush unit comprising a generally cylindrical core and an annular brush element seated on the outer periphery of said core with brush material extending generally radially therefrom, said core comprising a unitary cylinder having a plurality of radially uniform ribs projecting inwardly from its inner periphery and extending generally parallel to the axis thereof, said ribs being exposed and circumferentially spaced to engage and seat uniformly upon a rotary shaft inserted co-axially within said core.

30 6. An annular rotary brush comprising a generally cylindrical core with brush material extending radially outwardly therefrom, said core having rigid ribs exposed on its inner periphery extending generally parallel to the axis thereof circumferentially spaced to engage a shaft inserted co-axially within said core and firmly seat thereon, a shaft thus fitted in said core, and means on said shaft engaging at least one said rib to drive said core and brush therewith.

35 7. A rotary brush unit comprising a tubular metal core, a length of helically wound brush strip having a metal back seated on said core with brush material extending radially therefrom, the end turns of said helically wound brush back being locally welded to said core, and circumferentially spaced rigid internal projections on said core extending generally parallel to the axis thereof and exposed to engage circumferentially spaced regions of the peripheral surface of an arbor to support said unit centered thereon.

40 8. A rotary brush unit comprising a cylindrical core and an annular brush element seated on the outer periphery of said core with brush material extending generally radially therefrom, said core comprising a cylinder having a plurality of circumferentially spaced rigid ribs projecting inwardly from its inner periphery and extending generally parallel to the axis of said core, and an arbor of non-circular cross-section firmly seating said core with said ribs both drivingly engaging said arbor and also spacing the body of said core therefrom.

45 9. A rotary brush unit comprising a cylindrical core and an annular brush element seated on the outer periphery of said core with brush material extending generally radially therefrom, said core comprising two opposed identical sheet metal stampings of general half-circular cross-section with inwardly offset longitudinal edge portions circumferentially overlapping and joined

together, thereby providing two exposed diametrically opposite inwardly protruding ribs, inwardly protruding longitudinally extending ribs of like dimensions formed in each of said stampings midway between said first-named ribs, said ribs being exposed to engage and seat upon an arbor inserted within said core.

10. A rotary brush unit comprising a cylindrical core and an annular brush element seated on the outer periphery of said core with brush material extending generally radially outwardly therefrom, said core comprising a sheet metal cylinder having a plurality of exposed inwardly projecting ribs of substantial width formed therein by deformation of the sheet metal of said cylinder extending generally parallel to the axis thereof and circumferentially spaced to seat said core upon a power driven shaft inserted axially within said core, said cylindrical core also having apertures therethrough for passage of fluid from the interior to the exterior thereof.

11. A rotary brush unit comprising a rigid generally cylindrical core, and an annular brush element seated on

10

15

20

the outer periphery of said core with brush material extending generally radially outwardly therefrom, said core comprising a sheet metal cylinder having a plurality of inwardly projecting ribs of substantial width formed therein by deformation of the sheet metal of said cylinder and exposed in the central opening of the latter for driven engagement with a shaft of non-circular cross-section inserted co-axially therein.
